4 SHEETS—SHEET 4.

This technical drawing illustrates a mechanical assembly, likely a component of a larger machine. The drawing is oriented vertically and features several horizontal plates or frames. On the left side, there are two vertical columns of rectangular blocks, each containing a circular hole. The top block in the left column is labeled '47' and the bottom block is labeled '17'. Between these columns and the central structure are two vertical bars labeled '51'. The central part of the assembly consists of a rectangular frame with a hatched base. Inside this frame, there are two vertical bars labeled '28' and '29'. The top of the frame is labeled '48'. To the right of the central frame, there are two vertical columns of rectangular blocks, each containing a circular hole. The top block in the right column is labeled '52' and the bottom block is labeled '17'. Between these columns and the central structure are two vertical bars labeled '51'. The bottom of the frame is labeled '47'. The entire assembly is supported by a base with a hatched pattern.

UNITED STATES PATENT OFFICE.

CLAUDE EARLY FIELD, OF SLATER, MISSOURI.

BALING-PRESS.

No. 845,625.

Specification of Letters Patent.

Patented Feb. 26, 1907.

Application filed July 6, 1905. Serial No. 268,326.

To all whom it may concern:

Be it known that I, CLAUDE EARLY FIELD, a citizen of the United States, and a resident of Slater, in the county of Saline and State of Missouri, have invented a new and Improved 5 Baling-Press, of which the following is a full, clear, and exact description.

My invention relates to presses for baling hay, straw, and like material.

10 The purpose of the invention is to provide a construction of press in which a plunger is not employed and wherein the feed mechanism is such that the press can be fed at any time while in operation, it not being necessary to await the return of the plunger, as required in all the baling-presses of which I have knowledge.

Another purpose of the invention is to provide a construction of baling-press in which 20 the power is utilized at all times during its operation and wherein the feed is continuous, thus dispensing with the violent back stroke of a plunger, which tends to rapidly wear out and rack the machine.

25 A further purpose of the invention is to improve upon the formation of the spacing-blocks and to provide positive means for feeding them and the bales out from the machine and also to provide simple and effective means for wiring the bales and securing the wire on the bales.

The invention consists in the novel construction and combination of the several parts, as will be hereinafter fully set forth, 35 and pointed out in the claims.

Reference is to be had to the accompanying drawings, forming a part of this specification, in which similar characters of reference indicate corresponding parts in all the figures.

40 Figure 1 is a side elevation of the improved press. Fig. 2 is a plan view of the same. Fig. 3 is an enlarged longitudinal vertical section through the forward portion of the press, the section being taken practically on the line 3 3 of Fig. 4. Fig. 4 is an enlarged vertical transverse section taken substantially on the line 4 4 of Fig. 1. Fig. 5 is a horizontal section taken substantially on the line 5 5 of Fig. 3. Fig. 6 is a detail horizontal section taken practically on the line 6 6 of Fig. 3. Fig. 7 is a detail transverse section through one set of bale-feeding arms and a dog carried thereby. Fig. 8 is a diagrammatic view illustrating the manner in which the tie-wire for the bales is manipulated.

Fig. 9 is a perspective view of the instrument employed for drawing the wire through the spacing-blocks. Fig. 10 is a perspective of the bale-tie employed, and Fig. 11 is a perspective view of a modified form of spacing-blocks.

The body A of the press is carried by a truck B. In the construction of said truck the rear axle 10 is provided with supporting- 65 wheels 11 and a bolster 12, having a longitudinal recess 12^a in its upper surface. The forward axle 13 is provided with smaller wheels 13^a, a tongue or pole 14, and a bolster 15. The construction of the truck is completed by securing side beams 16 to the upper portion of the bolsters at their outer ends and attaching transverse sleepers 17 to the beams 16. The sleepers 17 are placed at pre-determined intervals apart and are of greatest depth at their central portions. The body A rests upon and is suitably attached to the sleepers 17, as is shown in Fig. 1.

That portion of the body containing the baling-chamber A' is made in two sections, 80 an upper section 18 and a lower section 19, and at the forward portion of the baling-chamber A' the sides of the sections 18 and 19 are brought sufficiently close together to form centrally-located longitudinal side slots 85 20, which connect at their forward ends with upwardly and forwardly inclined slots 21. Said slots 21 extend out through the body its entire width at the top, as is also shown in Fig. 1. The extreme rear portion of the body 90 A is in the form of an open horizontal platform 22, which constitutes a continuation of the floor of the baling-chamber A', while between the inner end of the platform 22 and the rear end of that portion of the body containing the slot 20 the sides of the body are 95 cut away, so as to expose a sufficient surface of the bales to enable them to be tied. The two sections 18 and 19 of the body are connected in any approved manner—as, for example, by securing transverse battens 23 on the top of the said body and connecting these battens with the sleepers 17 by means of rods 24.

The feed-chamber A² is at the forward end 105 of the body A and is in direct communication with the baling-chamber A'. The upper portion 25 of the feed-chamber A² is open and surrounded by a hopper 26, as is shown in Fig. 3. Parallel longitudinal slots 27 are 110 made in the bottom of the feed-chamber and the forward portion of the baling-chamber to

accommodate feed-fingers to be hereinafter described, and said parts are normally covered by a sheet 28, of rubber or other flexible elastic material, as is shown in Figs. 3, 4, 5 and 5.

Below the forward portion of the body A a rear shaft 29 and a forward shaft 30 are journaled in bearings located on the beams 16, the bearings being designated, respectively, 10 as 29^a and 30^a, and sprocket-wheels 31 are secured on the shaft 29, one near each end, while corresponding sprocket-wheels 32 are secured upon the shaft 30. The two shafts 29 and 30 are parallel, and chain belts 15 33 are passed over corresponding sprocket-wheels 31 and 32. These chain belts carry feed-fingers C, above referred to. These feed-fingers C are arranged in pairs and are located adjacent to the inner edges of the said 20 feed-belts, occupying such a position that as the belts 33 revolve the fingers extend up through the slots 27 in the bottom of the feed-chamber A², as is shown also in Fig. 3.

A longitudinal guide-block 34 is located 25 about midway between the belts 33, as is shown in Figs. 3, 4, and 6, the said guide-block being supported by a cross-bar 35, carried from one beam 16 to the other. The feed-fingers C are of angular formation, comprising a long member c and a short member c', the short member being at right angles to the long member, as is best shown in Fig. 3. The feed-fingers of a pair are placed one parallel with the other, and pins 36 are passed 30 through eyes formed at the junction of the members of the said fingers. The said pins 36 are secured in any suitable or approved manner to the chain belts 33, as is shown in Fig. 3, and rollers 37 are mounted on the said 35 pins 36, turning loosely between the feed-fingers.

At the outer end of the shorter members c' of the feed-fingers C eyes are formed, and pins 38 are passed through said eyes. On 40 these pins 38 rollers 39 are mounted to loosely turn between the feed-fingers, the rollers 39 corresponding to the rollers 37. These rollers in the operation of the belts 33 engage with the marginal portions of the guide-block 45 34. This guide-block is of peculiar construction, and its construction is best shown in Fig. 3, wherein it will be observed that the top a of the block is straight, the upper rear corner a' is rounded, the rear end portion a² is straight, and the bottom a³ is likewise straight from the rear end of the block to an angular recess a⁴ made in the bottom forward portion of the said block, and the forward end of this reduced portion of the block 55 is curved upward to meet the straight upper surface a, as shown at a⁵, the curvature at the bottom being much sharper than the curve leading directly to the upper edge.

The shaft 29 is provided with a pulley 40 60 for belt connection with a motor, and said

shaft is also provided with a polygonal end section 40^a, so that horse-power may be employed, if desired. As the shaft 29 is rotated motion is imparted to the belts 33, which belts move in such direction as to cause the 70 uppermost feed-finger C to travel rearward. When the fingers are in their upper position, the larger members c extend up into the feed-chamber A² through the slots 27, forcing the cover-strip 28 to one side as they travel 75 along, as is shown in Figs. 3, 4, and 5, and the fingers C must thus force the material from the feed-chamber into the baling-chamber, as both rollers 37 and 39 of the pair of fingers will be in contact with the upper 80 straight edge a of the guide-block 34.

As the upper stretches of the chain belts 33 move forward the roller 39 will move on the guide-block at its rounded rear corner a', whereupon the straw or hay will give the 85 members c of the fingers C a forward inclination, and as the pivoted portions of the fingers are carried downward the members c will gradually straighten, since said members will be brought against the rear end walls of 90 the slots 27; but the moment the said members c of the fingers C clear the slots 27 said members c will drop downward and assume the lower position shown in Fig. 3. When the members c of the fingers C strike the 95 lower edge of the recess 12^a in the bolster 12, the members c' will be brought to a substantially vertical position, the rollers 39 then being in engagement with the lower edge a³ of the guide-block 34. When the recess a⁴ is 100 reached, the members c can drop, and as the belts rise at the front of the machine the rollers 39 of the short members c' engage with and ride upon the forward curved under surface a⁵ of the guide-block, bringing the members c of the fingers once more to the vertical 105 position at the top of the guide-block, also causing the said members c to enter the slots 27, take up the material in the feed-chamber A², and pass it into the baling-chamber A'. 110 In order that the fingers C may readily rise at the front portion of the machine, the forward sleeper 17 is provided with a concaved recess 40^b upon its inner face, as is shown in Fig. 3.

D represents a spacing block or board 115 which conforms to the shape of the baling-chamber A', but is of such dimensions as to have free sliding movement in said chamber. The spacing-block is provided at top and 120 bottom with a groove 41, and a wall at one side of each groove is deeper than the wall at the opposite side. The shorter wall is at the front portion of the block at the top and the rear portion of the block at the rear of the 125 machine, for example, as is illustrated in Fig. 3. The block D is provided with trunnions 42, centrally located in its side surfaces, and these trunnions extend out through the slots 20 when the board is in place in the said 130

baling-chamber A'. A spacing board or block D is introduced into the baling-chamber whenever sufficient material has been fed thereto to make a bale, and when introduced 5 the trunnions 42 are made to enter the inclined extensions 21 of the horizontal slots 20.

In Fig. 11 I have illustrated a modified form of the division board or block, (designated as D'.) This block is reduced in width at the 10 bottom, forming heads 44, and each head is provided with a groove 45, extending from one side of the block to the other. These 15 grooves receive the lower flanged portions of sliding caps 46, which caps are of such size that while they are flush with the side faces of the blocks they extend, respectively, beyond the upper and lower faces of the heads 44, so as to provide a space through which the wire 20 is to be drawn. After the material in the baling-chamber A' has been divided into 25 bales by the introduction of the division boards or blocks D it is desirable that the bales and boards be automatically discharged from the said chamber A', and this is accomplished by a pressing mechanism especially 30 designed for the purpose and which is particularly shown in Figs. 1, 2, 4, and 7. This mechanism is as follows: Two sets of feed-bars 47 and 48 are placed in parallelism, one 35 in front of the other at each side of the body A, extending from a point near the forward end to the rear of the slots 20, practically in registry with the lower walls of said slots, as is shown in Fig. 1. Each pair of arms at 40 their forward ends are provided with longitudinal slots 49 and at their rear ends with corresponding slots 50. These feed-bars 47 and 48 have simultaneous sliding movement in opposite directions, and their movements 45 are limited by check-screws 51 and 52 or their equivalents—as, for example, sheaved rollers on screws or pins—the screws 51 being passed through the slots 49 and the screws 52 through the slots 50, all the screws entering 50 the body A. A press-bar of each pair 47 and 48 is provided with two parallel downwardly-extending contact-arms, the arms of the bars 47 being designated as 47^a and the arms of the bars 48 as 48^a. A series of dogs 53 of an- 55 gular formation are pivoted between the press-bars of each pair, their head portions being normally upwardly and rearwardly inclined, as is shown in Fig. 1, and as the feed-bars 47 and 48 move rearward the most convenient dogs 53 will engage with a trunnion of a spacing-block D, causing said block, and consequently the bale against which it bears, to be given a movement in direction of the platform 22 at the rear of the machine. At 60 the rearward movement of the said bars 47 and 48 the dogs 53 are held in positive position for engagement with the trunnions 42 of the spacing-blocks D by means of stop-pins 54, which engage the dogs below their pivots, 65 as is shown in Figs 1 and 7; but when the

said press-bars 47 and 48 are on their return or forward stroke their head portions simply slip by the trunnions 42 of the spacing-blocks D, having no action upon them and being uninterrupted in such action by said 70 stop-pins 54, which only act as specified.

The necessary movements are imparted to the press-bars 47 and 48 by securing cams 55 and 56 on the shaft 29 near each end, the lengthy portions of the cams extending in opposite directions, as is shown in Fig. 6. These cams are necessarily placed close together at each end of the shaft, and the cam 55 operates between the contact-arms 47^a of the press-bars 47, while the cams 56 operate between the contact-arms 48^a of the press-bars 48. Under this arrangement as the shaft 29 is revolved the cams simultaneously act to carry one pair of press-bars at each side of the machine rearwardly for action. 80 After the bales have been formed in the baling-chamber A' it is necessary to wire the 85 said bales, and this wiring process is carried out while the bales yet remain in the baling-chamber and when they have reached the 90 open side portions of said chamber, as is particularly shown in Fig. 1. Preferably at the left-hand side of the body at a point to the rear of its open side portions, two reels 57 and 58 are mounted to turn, the said reels carrying the tie-wire 59. These wires 59 are led from a reel through suitable guide-staples 60 or their equivalent to the said open portion 95 at the left-hand side of the body.

In wiring a bale an instrument E is employed. (Shown particularly in Fig. 9.) This instrument consists of a bar-body 61, preferably made flat and rectangular in cross-section, being pointed at one end and provided at the other end with an offset 62 at 100 right angles to the body proper, and the said bar-body 61 is likewise provided with a substantially V-shaped recess 63, produced in its upper edge adjacent to the point, and between the point and the said recess 63 a 105 clamping-finger 64 is pivoted to the bar-body, the clamping-finger having a recess 65 in its head or free portion and a semicircular recess 66 in its under face adjacent to the head. The clamping-finger 64 is pivotally 110 connected to one end of a rod 67, and this rod has free movement in the offset 62 and terminates in a suitable knob or handle 68. Upon drawing the rod 67 outward or away 115 from the point of the bar-body the clamping-finger is drawn downward over the recess 63, and the wire strand or wire which may have been passed over the lower portion of the said recess 63 will be held firmly by the clamping-finger in its lower position, as the 120 said finger straddles the bar-body to a greater or lesser extent. When the wire is thus caught and held, it can be manipulated 125 very readily and quickly released when desirable. This wire-drawer is made of such 130

dimensions that it can readily pass through the grooves 41 at the upper and lower portions of the spacing-blocks D and likewise through the upper and lower spaces provided 5 for its reception in the form of spacing-block D'. (Illustrated in Fig. 11.) After the wire has been properly passed around a bale its ends are connected by means of a bale-tie F. (Shown in detail in Fig. 10.) The tie is 10 made of soft metal, such as iron or brass, for example, has flat side faces 69, and may be of any desired length and breadth, but is of greater length than width. Two cuts 70 and 71 are made in the lower edge of the body, 15 diverging from a central point, and the cuts extend diagonally in direction of opposite corners, forming thereby two bills 72 and 73, which are initially bent outward beyond the plane of one side of the body, and in the 20 edges of each cut opposing concaved recessions are made to receive the loose wire and hold it. In the application of this tie the two ends of the wire are received in the spaces where the bills join the body at the 25 cuts 70 and 71. Then by means of a suitable instrument the bills are brought into the plane of the sides of the body, thereby clamping the wire. In order to insure a positive grip upon the wire, the bills are 30 forced upon that portion of the body above them, as is shown in Fig. 1.

When the baling operation has been commenced, enough wire is reeled off to permit the wire to be bent upon itself and to pass 35 through the open portion of the baling-chamber to and beyond its right-hand side, whereupon the end of the wire is bent, as is shown at b to the left in Fig. 8. As the rear end of the first bale is received in the loops 40 thus formed in the wires 59 the wires are reeled off until the spacing-block D at the forward end of the bale reaches the open space in the side of the baling-chamber, whereupon the instrument E (shown in Fig. 45 8) is passed, for example, through the upper groove 41 in the said block, and the wire is gripped by the jaw or clamping-finger 64 of the said instrument, as is shown in Fig. 2. The wire is then drawn through the said upper groove 41 to the right-hand side of the press, as is shown to the left in Fig. 8, and enough wire is then drawn through to extend some distance beyond the side of the bale. The wire is next cut where it is gripped 50 by the instrument, and the forward strand is then bent, as shown at b, to receive the next bale, while the rear portion of the cut wire is bent to meet the first or rear bend, and the two ends of the wire are then brought together 55 and secured by the tie F in the manner which has been described. The operation of the instrument E is then repeated at the bottom groove in the spacing-block. When a spacing-block is to be removed from 60 the bale, the wire will readily slip over the 65

short wall of the lower groove, for example, whereupon the longer wall at the upper groove in the said block can be readily worked out through the wire.

In Fig. 1 I have illustrated an inclined 70 platform G, independent of the press and located at the rear thereof, which platform receives the completed bales from the machine-platform 22. The platform G may lead to a vehicle in which the bales are to be 75 placed.

I desire it understood that I do not restrict myself to the use of the fingers C in pairs, as they may be used singly or in groups of any 80 desired number.

Having thus described my invention, I claim as new and desire to secure by Letters Patent—

1. In a baling-press, a body-section provided with a feed-chamber and connecting 85 baling-chamber, the feed-chamber having slots in its bottom, a support for the said body, a flexible covering for the said slots, and a feed mechanism carried by the said support, which feed mechanism consists of parallel 90 shafts, a guide-block between the shafts, sprocket-wheels secured on the said shafts, endless-chain belts passed over the said sprocket-wheels, pins connecting the said belts, angular fingers loosely mounted in 95 series on the said pins at the junction of the members of the fingers, one member of a finger being long and the other short, a roller located between opposing fingers at the junction of their members, and a second 100 roller located between opposing fingers at the outer ends of the shorter members, the said rollers being adapted for engagement with the said guide-block and the longer members of the fingers being adapted to extend into 105 the feed-chamber through the slots therein.

2. In a baling-press, a body provided with a baling-chamber having longitudinal slots in its sides, and extensions from said slots leading to the top of the body, press-bars 110 located one back of the other and mounted to slide on the said body at the longitudinal slots therein, dogs pivoted on the said press-bars, having their working ends inclined rearward, a drive-shaft, and means for alternately reciprocating the press-bars from the 115 said drive-shaft in opposite directions.

3. In a baling-press, a body provided with a baling-chamber having longitudinal slots in its sides, and extensions from said slots 120 leading to the top of the body, press-bars located one back of the other and mounted to slide on the said body at the longitudinal slots therein, dogs pivoted on the said press-bars, having their working ends inclined 125 rearward, a drive-shaft, means for alternately reciprocating the press-bars from the said drive-shaft in opposite directions, spacing-blocks located in the said baling-chamber, and trunnions extending from the sides 130

- of the said blocks out through the said longitudinal slots in the body, which trunnions are engaged by the dogs at the rearward movement of the said feed-bars.
- 5 4. In a baling-press, the combination with a body provided with a feed-chamber and a baling-chamber, the said body being provided with longitudinal slots in its sides, leading into the baling-chamber, and inclined extension-slots leading from the forward ends of the longitudinal slots out through the top of the body, a support for the body, a drive-shaft mounted on said support, and cams secured to the said shaft, the cams being in pairs, the cams of a pair extending in opposite directions, of press-bars arranged one back of the other at the sides of the body, being mounted to slide on said body, their upper edges being substantially parallel with the lower edges of the said longitudinal slots in the body, angular dogs pivoted on the said bars, extending above and below the bars, the head portions of the dogs being inclined rearwardly, connections between the said bars and the said cams, whereby to simultaneously and alternately operate the said bars in opposite directions, and spacing-blocks located in the baling-chamber, having trunnions which extend out through the said slots 30 in the said chamber, to be engaged by the heads of the said dogs.
5. In a baling-press, the combination with a body provided with a feed-chamber and a baling-chamber, the said body being provided with longitudinal slots in its sides leading into the baling-chamber and inclined extension-slots leading from the forward ends of the longitudinal slots out through the top of the body, a support for the body, a drive-shaft mounted on said support, and cams secured to the said shaft, the cams being in pairs, the cams of a pair operating in opposite directions, of press-bars arranged one back of the other at the sides of the body, being mounted to slide on said body, their upper edges being substantially parallel with the lower edges of the said longitudinal slots in the body, angular dogs pivoted on the said bars, extending above and below the bars, the head portions of the dogs being inclined rearwardly, spacing-blocks mounted to slide in the baling-chamber, trunnions extending from the said spacing-blocks out through the slots in the body, adapted to be engaged by the said dogs at the rearward movement of the said dogs, stop-pins for the said dogs,

limiting their downward and rearward movement, and contact-arms extending down from the said bars to an engagement with the said cams, each cam operating between the contact-arms of a pair.

6. In a baling-press, a baling-chamber having longitudinal slots in its sides, spacing-blocks mounted to slide in the chamber and provided with trunnions projecting through the said slots, and means for engaging the trunnions of the blocks to operate the said blocks.

7. In a baling-press, a baling-chamber having longitudinal slots in its sides, spacing-blocks in the chamber and having trunnions projecting through the said slots and reciprocating bars provided with means for engaging the trunnions of the blocks.

8. In a baling-press, a baling-chamber having longitudinal slots in its sides, spacing-blocks in the chamber and having trunnions projecting through the said slots, reciprocating bars, and pivoted dogs on the reciprocating bars and engaging the trunnions of the blocks.

9. In a baling-press, a feed-chamber having longitudinal slots in its bottom, a sheet of flexible material in the bottom of said chamber, spaced endless belts below the feed-chamber, angular fingers carried by the belts and arranged in pairs, and a guide-block between the belts.

10. In a baling-press, a feed-chamber having longitudinal slots in its bottom, one at each side, a sheet of flexible material secured in the bottom of said chamber at its longitudinal center, endless feed-belts below the feed-chamber, and fingers arranged in pairs and carried by the belts, said fingers projecting through the slots of the feed-chamber into the same.

11. In a baling-press, a feed-chamber having a longitudinally-slotted bottom, a sheet of flexible material in the bottom of the feed-chamber, and endless belts below the feed-chamber and provided with fingers projecting through the slots of said feed-chamber into the same.

In testimony whereof I have signed my name to this specification in the presence of two subscribing witnesses.
